(57) **CLAIM**

The ornamental design for a portable power device, as shown and described.

DESCRIPTION

FIG. 1 is a perspective view of a portable power device; FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines in the drawings illustrate portions of the portable power device which form no part of the claimed design.
